US00D738887S

(12) **United States Design Patent**
Ma et al.

(10) **Patent No.:** US D738,887 S
(45) **Date of Patent:** ** Sep. 15, 2015

(54) **DIGITAL CAMERA WITH A GRAPHICAL USER INTERFACE**

(71) Applicant: **Samsung Electronics Co., Ltd.**, Suwon-Si, Gyeonggi-Do (KR)

(72) Inventors: **Cho Hyang Ma**, Yongin-si (KR); **Jee-Yeon Wang**, Seoul (KR); **Joong hun Kwon**, Seoul (KR)

(73) Assignee: **SAMSUNG ELECTRONICS CO., LTD.**, Gyeonggi-Do (KR)

(**) Term: **14 Years**

(21) Appl. No.: **29/445,209**

(22) Filed: **Feb. 8, 2013**

(30) **Foreign Application Priority Data**

Aug. 29, 2012 (KR) 30-2012-0041619

(51) **LOC (10) Cl.** **14-04**

(52) **U.S. Cl.**

USPC **D14/485**

(58) **Field of Classification Search**

USPC D14/485-495

CPC ... G06F 3/048; G06F 3/0481; G06F 3/04817; G06F 3/0482

(57) **CLAIM**

The ornamental design for a digital camera with graphical user interface, as shown and described.

DESCRIPTION

The single FIGURE is a front-side view of a digital camera with a graphical user interface showing our new design. The broken lines shown in the drawing illustrate the digital camera and form no part of the claimed design.

1 Claim, 1 Drawing Sheet
